UNITED STATES PATENT OFFICE

2,078,227

CIGAR AND WRAPPER

Harry Blum, New York, N. Y., assignor to Harry Blum's Natural Bloom, Inc., New York, N. Y., a corporation of New York

Application August 5, 1935, Serial No. 34,817

6 Claims. (Cl. 131—11)

This invention relates to an improved cigar and wrapper and one object of the invention is to provide a cigar which is wrapped in a special manner and may consist of companion sections formed separately and of less length than usual or formed from a cigar of more than usual length and cut intermediate its length to provide the companion cigar sections, the cigar being enclosed in a wrapper of such construction that a portion enclosing one cigar section may be detached and the cigar section enclosed therein smoked while the other cigar section remains in the portion of the wrapper enclosing the same.

It will thus be seen that a person purchasing the improved cigar may smoke one half or section thereof and the other section later on without the second cigar section being spoiled due to smoking the first section. This will be greatly appreciated by persons desiring a short smoke. The improved wrapper will also reduce the cost to a manufacturer making cigars to be sold in groups of two as both cigars will be enclosed in a single wrapper and thus the cost of wrappers and the labor of wrapping cigars reduced. While it is stated above that two cigars or cigar sections are to be enclosed in a single wrapper it will be obvious that a greater number of full length or short cigars may be enclosed in a wrapper or a cigar of more than the usual length cut into more than two sections.

Another object of the invention is to provide a wrapper of such construction that portions thereof between cigar sections will be weakened and thus allow the wrapper sections to be easily separated when grasped about adjacent portions of the cigar sections and force exerted transversely thereof.

A further object of the invention is the provision of a wrapper having scored portions between cigar sections to permit easy separation rupture of the wrapper between the cigar sections, the scored portion of the wrapper being encircled by a band or having a representation of a band painted or printed thereon to seal the scored portion and prevent passage of air or moisture through the same and also serve to reinforce the scored portion and prevent accidental fracture of the wrapper when a wrapped cigar is carried in a pocket or carelessly handled.

Still another object of the invention resides in

providing a construction which is simple and durable, inexpensive to manufacture and one which will be very efficient in use.

With these and numerous other objects in view, my invention consists in the novel features of construction, combination and arrangement of parts as will be hereinafter referred to and more particularly pointed out in the specification and claims.

The invention is illustrated in the accompanying drawing wherein:

Figure 1 is a view looking down upon a cigar of the improved construction in the improved wrapper;

Figure 2 is a view taken at right angles to Figure 1 and looking at a side of the improved cigar and wrapper;

Figure 3 is a view showing the cigar and wrapper partially in side elevation and partially in longitudinal section;

Figure 4 is a fragmentary view illustrating the manner in which the wrapper is fractured between cigar sections;

Figure 5 is an enlarged fragmentary section taken longitudinally through the wrapper and adjoining portions of the cigar sections;

Figure 6 is a view similar to Figure 5 showing the wrapper fractured between the cigar sections;

Figure 7 is a sectional view taken along the line 7—7 of Figure 5; and

Figure 8 is a fragmentary view showing a band disposed about the wrapper in encircling relation to the scored portion thereof.

In describing the invention, I shall refer to the drawing in which similar reference characters designate corresponding parts throughout the several views.

The cigar which is enclosed in the improved wrapper is of special form and consists of sections 1 and 2 each of which is preferably of less length than a cigar of standard length but may be of the standard length if so desired. The cigar sections may be formed separate from each other but are preferably formed as an overlength cigar which is sealed at both ends and cut transversely midway its length to provide two sections entirely separated from each other. By forming an overlength cigar and then cutting the same midway its length two cigars which may be referred to as cigar sections can

be very easily made and thus will insure provision of companion cigars of an even thickness to be enclosed in a single wrapper.

The wrapper 3 is preferably formed of cellophane although any thin transparent material may be used and is of such length and diameter that the cigar sections or companion cigars may be placed within the wrapper as shown in Figure 3 and end portions of the wrapper then folded as shown at 4 and secured to close ends of the wrapper and entirely enclose the cigars. Midway its length the wrapper of thin air and moisture proof material is scored as shown at 5 and as the scoring extends entirely about the wrapper, the wrapper may be grasped about adjoining end portions of the cigars and a slight force exerted transversely of the wrapped cigars will cause the wrapper to fracture along the scoring and divide the wrapper into separated sections 3^a and 3^b, each of which encloses one of the cigars but is open at one end. A cigar to be smoked can then be removed from the wrapper section in which it is enclosed and the other cigar put away for use at another time. As the cigar which is reserved for future use will be within a wrapper section it will be prevented from becoming soiled and to a large extent kept fresh.

Each cigar or only one of the cigar sections 30 may be banded with an identifying band as shown at 6 and a corresponding representation of a cigar band painted or printed upon the weakened intermediate portion of the wrapper as shown at 7. The material used in painting or printing upon the weakened intermediate portion of the wrapper is applied in liquid form and permitted to set, thereby providing a reinforcement of moisture-proof and air-impervious sealing material for the wrapper at the scoring. 40 This representation of a cigar band extends entirely about the wrapper and upon referring to Figures 3 and 5 it will be seen that a portion 7' thereof overlies the line of scoring 5. Therefore, a very effective seal will be provided for the scoring and prevent any danger of air or moisture leaking through the scored portion of the wrapper. It should also be noted that the scored portion of the wrapper will be reinforced and 45 accidental fracture of the wrapper prevented if the wrapped cigars are carelessly handled or carried in a pocket. Instead of printing or painting a representation of a cigar band upon the wrapper a band 8 corresponding to the band 6 but slightly larger may be fitted about the intermediate portion of the wrapper. This band fits snugly about the wrapper and will serve to reinforce the weakened portion of the wrapper and also serve as a closure to prevent air and moisture from leaking through the line of 50 scoring. The wrapper may be fractured along the line of scoring with the band 8 in place but this band will preferably be slid along the wrapper out of position about the weakened portion of the wrapper when it is desired to break the wrapper into sections and use one of the cigars.

From the foregoing description of the construction of my improved device, the application of the same to use will be readily understood. It will be seen that I have provided a 55 simple, inexpensive and efficient means for carrying out the objects of the invention.

While I have particularly described the elements best adapted to perform the functions set forth, it is obvious that various changes in form, 70 proportion and in the minor details of construc-

tion may be resorted to without departing from the spirit or sacrificing any of the principles of the invention.

Having thus described the invention what is claimed is:

1. An article of manufacture comprising a cigar consisting of companion sections disposed in longitudinal alignment with adjoining ends free, and a wrapper enclosing said cigar and formed of transparent air and moisture-proof material, portions of the wrapper between adjoining ends of the cigar sections being weakened by scoring extending transversely about the wrapper whereby the cigar sections may be grasped and slight force exerted transversely thereof to rupture the wrapper at the scored portion and provide separate wrapper sections each open at one end and containing one of said cigar sections, and identifying means for the cigar consisting of set material applied in a liquid or plastic state to the portion of the wrapper extending about adjoining ends of the cigar sections and covering the scored portion of the wrapper to reinforce the same against accidental fracture and when set serve as a seal to prevent passage of air and moisture through the scored portion. 15

2. An article of manufacture comprising a cigar consisting of companion sections disposed in longitudinal alignment with adjoining ends free, and a wrapper enclosing said cigar and formed of transparent air and moisture-proof material, the wrapper being closed at its ends and the portion of the wrapper between adjoining ends of the cigar sections being weakened by a line of perforations extending about the wrapper whereby the cigar sections may be grasped and slight force exerted transversely thereof to rupture the wrapper at the scored portion and provide separate wrapper sections each open at one end and containing one of said cigar sections, 30 and a band of set liquid and moisture-proof material fitting about the wrapper in covering relation to the scored portion thereof to prevent passage of air and moisture through the perforations and reinforce the perforated portion of the wrapper against accidental fracture. 35

3. A cigar wrapper having a weakened portion intermediate its length extending around the wrapper whereby it may be fractured at the weakened portion and divided into sections, and a 40 moisture and leak proof seal around the weakened portion, said seal consisting solely of printing or painting material applied to the wrapper in a liquid or plastic state and allowed to dry thereon. 50

4. A plurality of cigars disposed in longitudinal alignment with adjoining ends in close proximity to each other, a wrapper enclosing said cigars, the wrapper being weakened by scoring extending about the wrapper between adjoining 60 ends of the cigars whereby the wrapper may be disrupted by force exerted transversely of the cigars, and identifying means consisting of set liquid material adapted to reinforce the wrapper at the scoring extending entirely about the wrapper and covering the scored portions of the 65 wrapper to seal the scored portions against passage of air and moisture and prevent accidental fracture of the wrapper. 70

5. A cigar wrapper formed of transparent material and weakened by a scoring extending circumferentially about the wrapper intermediate its length, the weakened intermediate portion of the wrapper being provided with a simulation of a cigar band forming a moisture-proof and leak-

proof seal extending circumferentially around the wrapper to prevent air and moisture from passing through the scored portion of the wrapper, said seal consisting solely of set material applied to the outer face of the wrapper in a liquid or plastic state and allowed to set.

6. A cigar wrapper formed of transparent ma-

terial and having a weakened perforated portion intermediate its length extending about the wrapper for a major portion of the circumference thereof whereby it may be easily broken, said weakened portion having a covering of originally liquid or plastic material in set form.

HARRY BLUM.
